CAR-DOOR MECHANISM.

Application filed March 8, 1926. Serial No. 93,282.

Our invention relates to car door mechanism for supporting the drop doors of railway cars against opening movement, and has for its object to provide a mechanism for 5 that purpose which is of simple and rugged form and is easily operated.

The principal feature of the invention, generally stated, consists in rigidly mounting upon the door a bracket carrying a pivoted latch and a rotatable cam, the latch extending beyond the adjacent edge of the door so as to cooperate with a shouldered member secured to the car body for the purpose of maintaining the door in closed position, the 10 rotatable cam being adapted to engage the latch to retain the latter in door locking position, the latch and shouldered member being capable of having a locking engagement with each other in a plurality of relations corresponding respectively to closed 15 and partially closed positions of the door, and the latch and shouldered member having portions adapted to be simultaneously engaged by a removable lever serving as a 20 means for forcing the door to fully closed 25 position from a position of partial closure.

A further feature of the invention consists in mounting upon the door a bracket carrying a pivoted latch adapted to cooperate 30 with a bracket attached to the car body so as to prevent opening movement of the door, the bracket which is carried by the door being provided with a latch guiding portion forming means for supporting the 35 latch against outward thrust normal to its plane of operation, and the pivoted latch being maintained in door locking position by 40 means of a cam rotatably mounted on the first named bracket and adapted to engage the latch between its pivotal point and the 45 said latch guiding portion of the bracket.

Other features of the invention pertaining to advantageous forms and relations of parts will hereinafter appear and be pointed out 50 in the claims.

In the drawings illustrating a preferred embodiment of the invention,—

Figure 1 is a fragmentary view partly in side elevation and partly in section of one of

the hoppers of a railway car of a familiar 50 type, showing mechanism involving the invention applied thereto.

Figure 2 is a fragmentary end elevational view of the construction shown in Fig. 1.

Figure 3 is a sectional view on the line 55 3—3, Fig. 1.

Figure 4 is a detail elevational view of the bracket upon which the pivoted latch and its controlling cam are mounted.

Figure 5 is a detail view in end elevation 60 of the bracket shown in Fig. 4.

The car illustrated in the drawings is of the well known type having hoppers formed with sloping side walls, but it is to be understood that the invention is not limited in its 65 application to cars of that particular type; and while a portion of the door at one side only of the car is illustrated, it will be understood that the door construction on the opposite side of the car is identical. 70

In the construction illustrated, 1 indicates the side wall or sheet of a car hopper, and 2 is a door for closing the hopper discharge opening. The door, which is adapted to swing to open position under the influence of 75 gravity, may be hinged to the car body in any customary or preferred manner. The door is preferably of the sheet metal type having marginal stiffening flanges 3 which also serve as sealing means for preventing the escape 80 of fine lading. The marginal door flange 4, which is remote from the hinge axis of the door, preferably extends inwardly as shown.

Secured to the outer face of the door adjacent its lower edge is a stiffener or door 85 spreader 5 which may advantageously be in the form of a channel member having oppositely extending supplemental flanges 6 that bear against and are riveted to the door plate.

As is well understood, when the stiffening 90 member 5 serves as a door spreader it extends transversely of the car and is rigidly connected to the sections of the door on opposite sides of the car center sills so as to cause the door sections to operate as a unit. Rigidly 95 mounted upon the end of the stiffener 5 adjacent the side edge of the door is a bracket 7 carrying a pivoted latch 8 and a rotatable

cam 9 serving to retain the latch in door locking position. This bracket preferably is provided with inwardly directed spaced flanges 10 and 11 which receive the channel 5 portion of the door stiffener 5 between them, rivets 12 which extend through said flanges and stiffener being employed to secure the bracket in place.

The inwardly extending flanges 11 form 10 parts of horizontally spaced latch guides 13 and 14, respectively, with which the bracket 7 is integrally provided. The outer latch guiding portion 13 of the bracket serves to support the latch 8 against any outward 15 thrust normal to its plane of operation to which it may be subjected.

For the purpose of pivotally mounting the latch 8 the inner guide portion 14 of the bracket is preferably provided with a hollow 20 pivot stud or pintle 15 whose inner end terminates at the outer face of the door stiffener 5 when the parts are in assembled relation. The eye 16 at the inner end of the latch 8 receives the pintle 15 and a rivet 17 extending therethrough and through the door stiffener is preferably employed as security against bending or breaking of the pintle. To provide a pivotal mounting for the cam 9 by which the latch 8 is maintained in locked position, the bracket 7 is preferably fashioned with an upwardly directed flange 18 from which a forwardly projecting hollow pintle 19 extends. The cam may be conveniently retained in assembled position upon this pintle by means of an overlying washer 20 through which and through the hollow pintle and flange 18 of the bracket a rivet 21 passes. To limit the extent of downward swinging movement of the latch 8 when the door is open 40 an inwardly projecting stop lug 22 may be conveniently formed integral with the latch guide 13 so as to extend beneath the latch.

The cam 9 engages the latch intermediate of the pivotal point of the latter and the latch guiding portion 13 of the bracket. It is preferably formed with an opening 23 which, when the parts are in locked relation, is adapted to register with an opening 24 in the upstanding flange 18 of the bracket, said opening being adapted to receive a car seal of any usual or desired form. To compensate for variations in the position of the cam 9 when the latter is performing its duty of maintaining the latch 8 in door locking position, one 50 of the seal receiving openings 23 and 24, preferably the latter, may be elongated as shown.

The latch 8 projects laterally beyond the adjacent edge of the door and the neighboring side sheet 1 of the car. At its free end 60 it is provided with a seat for cooperating with a removable door operating lever by means of which the door may be forced from partially closed to fully closed position. This lever seat upon the latch may advantageously be formed as a perforated projection or loop

25 through which the door prying lever may be inserted, the lever thus being enabled to be employed not only for closing the door but also for prying a frozen door open.

Rigidly mounted upon the side sheet 1 of 70 the car body and projecting beyond the plane of the door for cooperating with the latch to prevent opening movement of the door is a shouldered member or bracket 26. This bracket and the latch are preferably adapted 75 to have locking engagement with each other in a plurality of positions respectively corresponding to closed and partially closed positions of the door. To this end the bracket 26 is provided with stepped shoulders 27 80 and 28, respectively, and the latch 8 is of a cross sectional form to afford corresponding cooperating stepped shoulders 29 and 30, respectively. When the inner shoulder 30 of the latch cooperates with the outer shoulder 85 of the bracket 26 carried by the car body the door is supported in partially closed position. When both shoulders 27 and 28 of the bracket respectively cooperate with the two stepped shoulders 29 and 30 of the latch 8 the door 90 is maintained in fully closed position. To constitute a fulcrum for the removable door operating lever when the latter is inserted in the perforated outer end 25 of the latch 28, the fixed door locking bracket 26 carried by the 95 car body is provided below its inner locking face 30 with an outstanding projection 31 which may advantageously be in the form of an upwardly opening pocket for receiving the lower end of the door operating lever. A 100 drainage opening 32 is preferably provided in the bottom of the pocket. As will be readily appreciated, a fulcrum formed as a lever receiving pocket efficiently lends itself to cooperation with the lever in prying a frozen 105 door open as well as in forcing the door completely shut. The outer end of the bracket 26 is preferably inclined, as at 33, to form an approach plane automatically causing the latch 8 to perform an unlocking movement 110 when the door is swung toward closed position. During this automatic unlocking rotation of the latch, the guide 13 effectively prevents movement of the latch outwardly 115 away from the door.

We claim:

1. In car door mechanism, the combination with a hinged door adapted to swing to open position under the influence of gravity, of a bracket rigidly mounted on the door, a latch pivotally mounted on the bracket and projecting beyond the adjacent edge of the door, movable means for engaging the latch to retain the latter in door locking position, and a bracket secured to the car body and projecting beyond the plane of the door for cooperating with the latch to prevent opening movement of the door, said last named bracket being provided with stepped shoulders and said latch being formed with correspondingly 130

stepped shoulders, and one of the shoulders of the latch being adapted to cooperate alternately with each of said shoulders of the bracket, whereby the door may be retained either in closed or in partly closed position.

2. In car door mechanism, the combination with a hinged door adapted to swing to open position under the influence of gravity, of a bracket rigidly mounted on the door, a latch 10 pivotally mounted on the bracket and projecting beyond the adjacent edge of the door, said latch being formed with an opening for receiving a removable door operating lever, a rotatable cam for engaging the latch to maintain the latter in door locking position, and a shouldered bracket rigidly secured to the car body and projecting beyond the plane of the door for cooperating with said latch to prevent opening movement of the door, said 20 bracket being provided with an outstanding projection constituting a fulcrum adapted to be engaged by a removable door operating lever when the latter is inserted in the said opening of the latch.

25 3. In car door mechanism, the combination with a hinged door, of a bracket carried by the door and rigidly secured thereto, a latch pivotally mounted upon the bracket, a cam rotatably mounted on said bracket and adapted to engage the latch to maintain the latter in door locking position, and a bracket secured to the car body and having a shoulder for cooperating with the latch to prevent opening movement of the door, said first 30 named bracket being provided with a latch guiding portion forming means for supporting the latch against outward thrust normal to its plane of operation, and said cam being adapted to engage the latch intermediate of the pivotal point of the latch and the said latch guiding portion of the bracket.

4. In car door mechanism, the combination with a hinged door, of means for maintaining the door in closed position, said means 45 involving a pivotally mounted member and a fixed member adapted to engage each other to prevent opening movement of the door, one of said members being carried by the door and the other by the car body, movable means adapted to engage said pivotally mounted member to retain the latter in locked position, and a bracket forming a mounting for said movable means, said last named means and the bracket each being provided with an aperture for receiving a seal.

5. In car door mechanism, the combination with a hinged door, of means for maintaining the door in closed position, said means involving a pivotally mounted member and a fixed member adapted to engage each other to prevent opening movement of the door, one of said members being carried by the door and the other by the car body, a bracket upon 60 which said pivotally mounted member is mounted, and a

cam rotatably mounted on the bracket and 65 adapted to engage the pivotally mounted member to retain the latter in locked position, said bracket having an opening adapted to receive a seal and said cam being provided with an opening with which said opening in the cam is 70 adapted to register.

6. In car door mechanism, the combination with a door hinged to the car body, of a stiffening member secured to the outer face of the door adjacent the free edge of the latter, 75 a bracket mounted upon the stiffening member adjacent a side edge of the door, a latch pivotally mounted upon the bracket and adapted to swing in a plane substantially parallel to the plane of the door, a cam rotatably mounted on the bracket and adapted to engage the latch to prevent pivotal movement of the latter, said bracket being integrally provided with a plurality of spaced 80 pintles upon which the latch and cam are respectively mounted and a shouldered bracket secured to the car body for cooperating with the latch to prevent opening movement of the door.

7. In car door mechanism, the combination 90 with a door hinged to the car body, of means for maintaining the door in closed position, said means involving a pivotally mounted member and a fixed member adapted to engage each other to prevent opening movement of the door, one of said members being carried by the door and the other by the car body, a rotatable cam adapted to engage said pivotally mounted member to retain the latter in locked position, and a bracket upon which the pivotally mounted member and the cam are mounted, said bracket being integrally provided with a plurality of spaced pintles upon which said pivotally mounted member and cam are respectively mounted, the pintles extending in opposite directions from their points of attachment to the bracket.

8. A bracket for car door mechanism adapted to form a mounting for a pivotally mounted door locking member and a rotatable cam for 110 maintaining the door locking member in locked position, said bracket being provided with integrally connected pintles extending in opposite directions from their points of attachment to the bracket.

9. A railway car having a lading discharge opening, a hinged door for closing said opening, said door being movable to open position under the influence of gravity, and means for supporting the door in closed position involving a movable latch member mounted on the door and a fixed hook member mounted on the car body, said hook being provided with a laterally projecting pocket constituting a fulcrum for a removable prying lever.

10. A railway car having a lading discharge opening, a hinged door for closing said opening, said door being movable to open

position under the influence of gravity, means for supporting the door in closed position involving a pivoted latch member mounted on the door and a fixed hook member mounted on the car body, and a lateral projection formed on the hook constituting a pocket affording a fulcrum for a removable prying

lever, said hook being provided with a reinforcing web extending from said pocket substantially longitudinally of the hook. 10

In testimony whereof we affix our signatures.
